PORTABLE ELECTRIC HEATER

William J. Cook, Trumbull, Conn., assignor to
General Electric Company

Filed Nov. 18, 1971, Ser. No. 200,271

Term of patent 14 years

Int. Cl. D23—03

U.S. Cl. D23—122

Fig. 1.

Fig. 2.

Fig. 3.

Fig. 4.

Fig. 5.

Fig. 6.

FIG. 1 is a front elevational view of a portable electric heater embodying my new design;

FIG. 2 is a perspective view thereof;

FIG. 3 is a top plan view thereof;

FIG. 4 is a rear elevational view thereof;

FIG. 5 is a bottom plan view thereof;

FIG. 6 is a right side elevational view thereof; and

FIG. 7 is a right side elevational view thereof with the heater tilted on its stand.

I claim:

The ornamental design for a portable electric heater, substantially as shown.
